1 Claim. (Cl. 240—6.46)

This invention relates to a combination electric hand 10 torch and writing instrument.

It is well-known for a pocket torch to be a self-contained unit and this usually is in outward appearance of similar design to the common pocket fountain pen. It is often necessary or desirable to write in a badly illuminated working area, and at present the only satisfactory way of having both a writing implement and a torch is by carrying them as individual articles. This implies that when one wishes to write either both hands are occupied, one with the pen and the other with the torch, or as is more usual, even though often unsatisfactory, the flash light is rested on some nearby surface.

An object of this invention is to provide apparatus suitable for writing and which has its own self-contained illuminating device, and yet is simple to use and easily assembled.

This invention provides the combination of a writing implement with an electric hand torch, and includes a hollow cylindrical body adapted to receive an electrical power source and an ink reservoir, one end of the body having a nose cone for the reception of a centre hole electric light bulb for connection to the power source, and an ink flow tube passing through the centre hole of the bulb to allow ink to flow from the reservoir to the writing tip of the tube.

The invention will now be described, by way of example only, and with reference to the accompanying illustrative drawing which is a longitudinal sectional view of a combination electric hand torch and writing implement constructed according to this invention.

A hollow cylindrical casing 1 is made having two parts, a forward cylinder 1a and a rearward cylinder 1b joined by conventional screw threads at 1c. The casing 1, having a removable nose cone 2 and a removable end button cap 3, contains in the rearward cylinder 1b a portable electrical power source 4 (which in this case is shown as two dry cell batteries electrically connected in series), and contains in the forward cylinder 1a an ink reservoir 5 and an electrically conducting case 6. A nose cone 2, which is removably attached by conventional screw or other suitable means at 2a to the cylinder 1a of the casing, has an outer protective nose cone 7 and contains within its interior a centre hole electric light bulb 8 which is screwed in the conventional manner into a metallic diaphragm 8a, which diaphragm is in itself an extension of an insulated electrical conduit 9. The centre hole bulb 8 is thus electrically connected through the electrically conducting casing 6 and electrical conduits 8a and 9 to the power source 4 via an on/off press button switch 10.

By depressing button 10 against a spring 11 a rod or stub 13 moves the batteries 4 in the direction of the nose cone 2 and against the action of a spring 12 (which spring is supported on an annular extension 12a of the casing part 1b), and thus an electrical contact is made between the casing 6 and the electrode 14 of the forward battery. A continuous electrical circuit is formed and the bulb lights. The bulb is turned off by depressing button 10 even further which releases a catch (not shown but is similar to that which is well-known in the design of retractable ball point pens and the like), the rod 13

2

retracts under the action of the spring 11 and the batteries 4 also retract under the action of the spring 12, thus breaking the electrical contact between 6 and 14 and the light from the bulb 8 is extinguished.

5 The ink reservoir 5, which in this case is shown having a larger cross-sectional area than that which is normally employed in the conventional fountain pen (thus allowing for any decrease in length of the reservoir which may be required, depending upon the size of batteries and length of the casing 1), has associated with it an ink flow tube 15 through which ink can flow to the writing tip 16.

The bottom 5a of the reservoir 5 is adapted for receiving a screw 17 which passes through an extension plate 18a of a control arm 18, and adjustably secures one to the other. The control arm 18 is attached to a sliding lever 19, movement of which lever causes the arm 18 to move forwardly in the direction of the nose cone 2 and in doing so causes the ink reservoir, flow tube and writing tip to move forward. The ink flow tube 15 thus passes through the centre hole of the bulb 8 and emerges through the hole 2b of the nose cone 2. Writing may commence once the protective cover 7 has been removed. Similarly the writing tip is retracted by moving the lever 19 in the reverse direction. The lever 19, which also serves as a pocket clip, may be locked in either the operable or inoperable position in any of the conventional ways.

As is usual in pocket torches, a proportion of the body of the nose cone 2 is constructed in either opaque or translucent material, and the forward end is of transparent material and shaped to form a lens 2c.

When it is necessary to replace or recharge the electrical power source, in this case the batteries, the button cap 3 is unscrewed at 3a and the batteries 4 removed.

30 Similarly for recharging or replacing the ink reservoir 5 the parts 1a and 1b of the casing 1 are separated by unscrewing at 1c, and this causes the ink reservoir 5, casing 6 and ink flow tube to emerge from the nose cone and centre hole bulb, since on unscrewing the parts 1a and 1b the reservoir is still indirectly attached to 1b by the control arm extension plate 18a. Once the ink reservoir has been exposed it is a simple matter to remove the electrically conducting casing 6 and replace the reservoir as in the case of ink cartridges, or recharge it in the case of "bottled ink."

45 The centre hole bulb may be replaced in the conventional manner by merely removing the nose cone 2 and unscrewing the bulb from the diaphragm 8a.

50 It should be realized that various modifications can be made to the construction of the apparatus as shown, for example, the screw 17 may, instead of making permanent contact, press against the bottom 5a of the ink reservoir 5, in which case a coil spring (not shown) would be placed around the ink flow tube 15 and thus force the reservoir backwardly when the lever 19 is moved backwardly.

55 What I claim is:

60 A combination writing implement and electric hand torch which includes a hollow cylindrical body adapted to receive an electrical power source and an ink reservoir; said nose cone removably attached to one end of said body, said nose cone defining a projection hole at the apex thereof; a centre hole electric light bulb located in and enclosed by said nose cone, the center hole of said bulb being in axial alignment with said projection hole; means 65 electrically connecting said bulb with said power source through a switch device; an ink flow tube located within and slidable through the center hole in said bulb and slidable through said projection hole, said tube communicating between at one end, said ink reservoir and the end remote therefrom, a writing tip whereby ink can flow

from said reservoir to said tip; control means operatively associated with said ink flow tube to slidably move said tube through said bulb to a position at which said tube projects through said projection hole and said tip is located externally of said nose cone, said tube being supported by said nose cone, and to slidably move said tube through said bulb from said projection position to a position in which said writing tip is located inside said nose cone at a position remote from said projection hole, said control means including an axially extending slideable lever located in said body, one end of said lever connecting said ink reservoir and the other end of said lever connecting through an axially extending elongated slot defined in a side of said body with a hand control knob, said hand control knob being slidably located on the exterior of 15 said cylindrical body.
